CLAIM

The ornamental design for a communication endpoint, as shown and described.

DESCRIPTION

FIG. 1 is a top view of a communication endpoint showing my new design with the movable display panel in an upright position:

FIG. 2 is a front view of thereof;

FIG. 3 is a back view thereof;

FIG. 4 is a bottom view thereof;

FIG. 5 is a left side view thereof;

FIG. 6 is a right side view thereof;

FIG. 7 is a top, front, and left side perspective view thereof;

FIG. 8 is a top, front, and right side perspective view thereof; and,

FIG. 9 is a top, front, and left side perspective view showing my new design with the movable display panel in a flat position.

The broken line showing of environmental structures is for illustrative purposes only and forms no part of the claimed design.
